MILLING MACHINE VISE

Frederick Koch, Sparta, N. J., assignor to Associated Patentees, Inc., Ampere, N. J., a corporation of New Jersey

Application October 28, 1939, Serial No. 301,697

9 Claims. (Cl. 90—60)

The invention here disclosed relates to vises and particularly though not exclusively to those of a type suitable for holding the work in milling machines.

Objects of the invention are to provide a quick acting vise, which can be readily set for holding work of different size, which in the holding position will have a high pressure factor, which will be automatically stopped to lock in the high pressure holding position, which will automatically hold in the adjusted position all the more firmly with increase of pressure on the stud which holds the vise set for different sizes of work and which with these and various other desirable attributes will be of relatively simple, substantial construction and consisting of but few parts.

The foregoing and other objects are attained by certain novel features of construction, combinations and relations of parts hereinafter described and broadly claimed.

The drawings accompanying and forming part of the following specification illustrate one of the present practical commercial embodiments of the invention. The structure however may be modified and changed as regards this disclosure all within the true intent of the invention, as will be apparent from the scope of the claims.

Figs. 1 and 2 are top plan views illustrating the invention embodied in the form of a milling machine vise and showing it in open and closed or substantially closed positions.

Fig. 3 is a longitudinal sectional view as on substantially the plane of line 3—3 of Fig. 1.

Fig. 4 is a cross-sectional view on substantially the plane of line 4—4 of Fig. 3.

Fig. 5 is a broken and part sectional detail illustrating the eccentric jaw closing mechanism.

In the embodiment illustrated, the base 7, of the vise is designed for mounting on a milling machine table and for that purpose is shown as of relatively flat elongated design, carrying a fixed jaw 8, at one end and recessed at 9, to take the bolts for fastening it down on the milling machine.

The movable jaw is shown at 10, slideable toward and away from the fixed jaw over the flat trackway 11, guided thereon by dependent flanges 12, reaching down over the side edges of the track as in Fig. 4 and confined in such relation by retainers 13, bolted to such dependent flanges and extending inwardly beneath confining shoulders 14, of the base.

Quick opening and closing jaw movements are effected in the illustration by means of a hand

lever 15, pivoted on a bushing or spacer sleeve 16, Fig. 3 and having an eccentric portion 17, Fig. 5, encircled by one end of a push link 18, which has its opposite end pivotally engaged with a pin 19, set in the movable jaw. This eccentric link is shown as supported on a shoulered portion 20, on the lever at the base of the eccentric and as loosely confined in this relation by a washer 21, resting on top of the sleeve 16, Figs. 3 and 4. At the opposite end, the link 18 enters through a recess 22, in the end of the movable jaw. The pivot pin 19, is shown in Fig. 3, as extending across the cavity 22, in the end of the jaw and as having a head 23, at the lower end of the same seating in a corresponding opening in the lower face of the jaw, such head sliding over the surface of the track 11, which latter thereby prevents escape of the pivot pin.

The eccentric jaw operating means disclosed provides a positive high pressure closing of the jaw and the hand lever enables quick easy operation of such means for either jaw closing or opening movements.

A shoulder 24, on the hand lever by engagement with the rear face of the movable jaw at 25, Fig. 5, limits the jaw closing movement of this lever and these cooperating parts are preferably so arranged as to engage just before the eccentric reaches the extreme limit of travel. This prevents the high point of the eccentric from passing the dead center position, thus to stop the parts in a locked relation just before reaching the extreme limit of travel, where pressure is practically at that maximum which is possible at the extreme end of eccentric travel.

For adjustment of the vise to different size pieces, the eccentric pivot is made adjustable, in the illustration by providing a bolt 26, carrying the pivot bushing 16. This bolt is shown as having a rectangular head portion 27, slidably and non-rotatably held in an intermediate slot 28, in the guide 11, and below that a widened or laterally extended head 29, engaged in the widened undercut groove 30. A nut 31, on the upper screw-threaded end of the bolt on the washer 21, to force the pivot bushing 16, down on the track 11, and to draw the head 29, on the lower end of the bolt firmly up against the roof 32, of the undercut slot 30. By loosening nut 31, the whole movable jaw assembly can be quickly shifted one way or the other to suit the size of piece to be held and by simply tightening this nut, the parts can be secured in position where the handle can be used to open and close the movable jaw to

release or to secure work of that particular size.

To lock the pivot stud in the position to which it is set, the undercut slot or at least the upper shoulders 32, of the same are inclined downwardly 5 away from the vise jaws on a slope such as represented by the line 33, Fig. 3 and the coacting upper face of the abutment head 29, is similarly inclined, thus to cooperate with a wedging effect upon application of jaw closing pressure. Stated 10 differently, the thrust of the jaw closing operation tending to shift the pivot stud away from the fixed jaw serves to bind the coacting wedge faces of the bolt head and undercut groove all the more firmly together. The reaction is a force 15 tending to elongate the bolt, which is made heavy enough to withstand any such action. Any tendency to slip will be immediately stopped by a wedging self-tightening cooperation of the parts.

20 The parts are proportioned so that the bushing will act as a spacing sleeve seating firmly down on top of the track 11, while leaving the lever free to oscillate thereon between said track at the bottom and the washer 21, at the top.

25 Similarly, the link 18 is left free on the eccentric 17, between the shoulder 20, on the hub of the lever and said confining washer 21.

Upon sufficiently loosening a nut 31, the handle 30 assembly with the attached movable jaw can be entirely withdrawn from the track portion of the base and when so removed, the pin 19, can be dropped or knocked out to release the movable jaw, thus to enable the ready substitution of a new or different jaw structure.

35 The device consists of but few simple sturdy parts easily produced at relatively low cost. These parts are readily assembled or disconnected, as may be required. The vise is quickly set to different sizes of work and when so set, is 40 easily opened and closed by simple swinging movements of the handle. Substantially maximum closing pressure of the eccentric is utilized and stopped at a position to automatically hold the parts in locked relation. The reaction force 45 on the movable jaw is utilized to effect a more secure holding of the vise in the adjusted position to which it has been set and any tendency to slip is made effective to automatically secure these parts the more firmly.

50 What is claimed is:

1. In a vise of the character disclosed, co-operating relatively movable jaws, an eccentric for applying jaw closing pressure and an adjustable mounting for said eccentric including a 55 support having a face inclined at a slight angle in respect to the jaw movement and a mounting stud for said eccentric having an abutment head in clamping engagement with said face and the inclination of said face being divergent in respect 60 to the jaw movement in the jaw opening direction, whereby to create the effect of a wedging engagement between the abutment head of said stud and said inclined face from reaction of the jaw closing pressure.

65 2. In a vise of the character disclosed, a base, fixed and movable jaws on said base, said movable jaw having a straight line movement on said base, a jaw closing lever connected to operate said movable jaw, a pivot mounting for said lever and 70 adjustable securing means for said pivot mounting, including a channel for said mounting in said base and inclined at a slightly divergent angle in respect to the jaw movement in the opening direction to effect wedging interlocking engagement of said pivot mounting on the base

as a result of the reaction of the movable jaw.

3. In a vise, a base having a track with an intermediate slot and a widened undercut groove below said slot, the roof of said undercut groove being inclined in respect to the face of said track, 5 a movable jaw slidingly confined to said track, a stud having a head slidingly and non-rotatably confined in said slot and an extended head portion received in said groove and engaged with the inclined roof of the same and means mounted on said stud for operating said movable jaw.

4. In a vise, a base having a track with an intermediate slot and a widened undercut groove below said slot, the roof of said undercut groove being inclined in respect to the face of said track, 15 a movable jaw slidingly confined to said track, a stud having a head slidingly and non-rotatably confined in said slot and an extended head portion received in said groove and engaged with the inclined roof of the same, means mounted on said stud for operating said movable jaw, said means including an eccentric pivotally supported on said stud and a link connection between said eccentric and said movable jaw.

5. In a vise, a base having a track with an intermediate slot and a widened undercut groove below said slot, the roof of said undercut groove being inclined in respect to the face of said track, a movable jaw slidingly confined to said track, a stud having a head slidingly and non-rotatably 30 confined in said slot and an extended head portion received in said groove and engaged with the inclined roof of the same, means mounted on said stud for operating said movable jaw, said means including an eccentric pivotally supported 35 on said stud, a link connection between said eccentric and said movable jaw and cooperating stops connected with said eccentric and movable jaw for limiting rotation of said eccentric to a point approximating the maximum throw of 40 the eccentric.

6. In a vise, a base having a track with an intermediate slot and a widened undercut groove below said slot, the roof of said undercut groove being inclined in respect to the face of said track, 45 a movable jaw slidingly confined to said track, a stud having a head slidingly and non-rotatably confined in said slot and an extended head portion received in said groove and engaged with the inclined roof of the same, means mounted on said stud for operating said movable jaw, said means including a spacer sleeve on said stud, a hand lever having an eccentric hub pivoted on said sleeve, a link engaged on said eccentric and connected with said movable jaw, a nut on said stud 50 and a washer secured by said nut in rigid engagement with said spacer sleeve and in free confining relation to said eccentric hub and the link engaged thereon.

7. In a vise, a base having a track with an intermediate slot and a widened undercut groove below said slot, the roof of said undercut groove being inclined in respect to the face of said track, a movable jaw slidingly confined to said track, a stud disposed in said slot and having an extended head portion received in said groove and engaged with the inclined roof of the same and means mounted on said stud for operating said movable jaw.

8. In a vise, a base having a track with an intermediate slot and a widened undercut groove below said slot, the roof of said undercut groove being inclined in respect to the face of said track, a movable jaw slidingly confined to said track, a stud disposed in said slot and having an ex- 70 75 75

- tended head portion received in said groove and engaged with the inclined roof of the same and means mounted on said stud for operating said movable jaw, said means including a spacer 5 sleeve on said stud and engaged with said track, a hand lever pivoted on said sleeve and having an eccentric portion, a link engaged on said eccentric portion and connected with said movable jaw, a nut on said stud and a washer secured 10 by said nut in rigid engagement with said spacer sleeve and in free confining relation to said lever and to the link engaged thereon.
9. In a vise, a base having a track with an intermediate slot and a widened undercut groove
- below said slot, a movable jaw slidingly confined to said track, a stud disposed in said slot and having an extended head portion received in said groove and means mounted on said stud for operating said movable jaw, said means including a spacer sleeve on said stud and engaged with said track, a hand lever pivoted on said sleeve and having an eccentric portion, a link engaged on said eccentric portion and connected with said movable jaw, a nut on said stud and a washer 10 secured by said nut in rigid engagement with said spacer sleeve and in free confining relation to said lever and to the link engaged thereon.
